UNITED STATES PATENT OFFICE.

STEPHEN J. FREEOUF, OF DORCHESTER, NEBRASKA.

AUTOMATIC REVERSING AND STOPPING MECHANISM.

1,277,564.

Specification of Letters Patent.

Patented Sept. 3, 1918.

Application filed April 17, 1917. Serial No. 162,629.

To all whom it may concern:

Be it known that I, STEPHEN J. FREEOUF, a citizen of the United States, residing at Dorchester, in the county of Saline and State of Nebraska, have invented new and useful Improvements in Automatic Reversing and Stopping Mechanisms, of which the following is a specification.

This invention relates to certain improvements in automatic reversing and stopping mechanisms, and has relation more particularly to a device of this general character especially designed and adapted for use in connection with straw spreaders or the like, and it is an object of the invention to provide a mechanism of this general character having novel and improved means whereby the same may effectively and conveniently be caused to impart movement to a member or 20 a gate in either direction, and wherein said reversal of movement may be automatically attained.

Another object of the invention is to provide a novel and improved mechanism of this general character wherein a member is caused to travel uninterruptedly in one direction, together with automatic means for reversing the direction of movement of the member, together with means for rendering 30 automatically the mechanism inoperative when said member has reached the limit of its movement in the second direction.

With these and other ends in view which will readily appear as the nature of the invention is better understood, the same consists in the improved construction and novel arrangement and combination of parts which will be hereinafter fully described and particularly pointed out in the claims.

40 In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the accompanying drawings:

Figure 1 is a side elevation of a device 50 constructed in accordance with the invention, parts having been broken away.

Fig. 2 is a top plan view, some parts having been broken away and others shown in section.

55 Fig. 3 is a rear elevation.

Fig. 4 is a diagrammatic view in side elevation of the speed regulating mechanism.

Fig. 5 is a diagrammatic view in side elevation of the mechanism for changing the direction of feed motion and for interrupting the same.

Fig. 6 is a plan view, enlarged, of the spring actuated bell crank controlling the feed motion.

Fig. 7 is a sectional view taken longitudinally through a portion of the main shaft.

Fig. 8 is a sectional view taken on the line 8—8 in Fig. 7.

Fig. 9 is a sectional detail view taken longitudinally through a portion of the countershaft.

Fig. 10 is a sectional detail view taken on the line 10—10 in Fig. 9.

Fig. 11 is a sectional detail view taken through a portion of the rear axle and the hub of one of the ground wheels to show the clutch mechanism.

Fig. 12 is a sectional detail view taken on the line 12—12 in Fig. 11.

Fig. 13 is a sectional view through one of the gate carriers, or carriages, taken on the line 13—13 in Fig. 1.

Fig. 14 is a sectional detail view taken on the line 14—14 in Fig. 13.

Corresponding parts in the several figures of the drawings are denoted by like characters of reference.

The rack or box of the improved device includes the main sills 15, rear cross bar 16, rear uprights 17, intermediate and front uprights 18 and 19, side boards 20, front boards 21 and a cap piece 22 whereby the upper ends of the rear uprights 17 are connected and spaced apart, said cap piece being supported directly above the rear cross-bar 16, 90 said cap and cross bar having their rear faces in substantially the same vertical plane. The rack or box is supported on front and rear axles 23 and 24, having ground wheels 25 and 26. Mounted on the axle 23 adjacent to one of the hind wheels 25 is a sprocket wheel 27 the hub of which is provided with spring actuated dogs 28 as best seen in Figs. 11 and 12, said dogs engaging a ratchet 29 on the hub of the ground wheel 25 so that by rotation of the latter in a forward direction the sprocket wheel 27 will be driven.

Fixed on the rear cross bar 16 are bearings 29' supporting the main shaft 30. Mounted 110

for rotation on the main shaft 30 is a sprocket wheel 31 which receives motion from the sprocket wheel 27 by means of a chain 32. Longitudinal movement of the 5 sprocket wheel 31 in one direction on the shaft 30 is limited by one of the bearings 29' and in the other direction by a collar 33 which is secured on the shaft by a pin or fastening member 34. A clutch member 35 10 which is slidable on the main shaft is provided with teeth 36 adapted to engage with similar teeth 37 on the hub of the sprocket wheel 31 which latter may thus be locked on the shaft for rotation therewith; the clutch 15 member 35 being slidably fitted on the shaft for rotation therewith as will be readily understood by reference to Figs. 7 and 8. The clutch member 35 is normally held in engagement with the clutch teeth of the 20 sprocket wheel 31 by means of a spring 38. For the purpose of actuating the clutch member against the tension of the spring 38 a slide 39 is provided having a forked end engaging an annular groove 40 in the clutch 25 member, said slide being connected by a link 41 with one arm of a bell crank 42 the other arm of which is connected by a rod 43 with a hand lever 44 which is mounted in convenient proximity to the driver's seat 45, 30 the latter being secured on the forward end of the box or rack.

A countershaft 46 is supported for rotation in bearings 47 in advance of the main shaft 30. A countershaft 46 carries sprocket 35 wheels 48 from which chains 49 are trained over sprocket wheels 50 on a shaft 51 which is mounted for rotation in bearings 52 near the front end of the rack, the parts being so arranged that the top leads of the chains 49 40 will pass above and the bottom leads below the floor or bottom member 52^a of the box or rack. Supported on the top face of said bottom member are longitudinal track bars or rails 53 on either of which moves a slide 45 or carriage 54 having a clamp 55 that engages the head of the rail or track bar and a grooved track-engaging wheel or roller 56. The two carriages 54 support the gate 57 which extends between the side walls of the 50 box or rack and which is maintained in an upright position by means of braces 58. The gate is securely connected in any convenient manner with the chains 49 as indicated at 58 so that when said chains are in motion the 55 gate will be moved forwardly or rearwardly in the box or rack according to the direction in which the chains are operated.

The countershaft 46 carries a sprocket wheel 59 and a ratchet wheel 60. The 60 sprocket wheel 59 is connected by a chain 61 with a sprocket wheel 62 on the main shaft from which it receives motion when said main shaft is being rotated. The ratchet wheel 60 carries on the hub thereof 65 a rocking lever 63 which is connected by a

pitman 64 with a crank 65 on the main shaft 30. The lever 63 also carries pawls or dogs 66 that engage diametrically opposite sides of the ratchet wheel 60, the arrangement of said dogs and of the teeth on the 70 ratchet wheel being such that the ratchet wheel will be rotated reversely to the movement of the sprocket wheel 59. The pitman 64 is adjustably connected with the crank 65 by a wrist pin 67 which is adjustable in a longitudinal slot 68 and the crank 65. The pitman 64 is also connected adjustably with the lever 63 by means of a pin 69 adjustable in a slot 70 in said lever, adjustment of said pin 69 being effected by 80 means of a link 71 connecting said pin with one arm of a bell crank 72 the other arm of which is connected by a rod 73 with a crank 74 on a rock shaft 75 which is supported in bearings near the forward end of the box or 85 rack and transversely across the same, said rock shaft having a hand lever 76 whereby it may be rocked to effect adjustment of the wrist pin 69 radially with respect to the ratchet wheel 60 for the purpose of varying the throw of the lever and thereby varying the degree of rotation of the ratchet wheel 60. The parts may be retained in adjusted position by means of a stop member 77 on the lever 76 engaging a rack segment 95 78.

The sprocket wheel 59 and the ratchet wheel 60 are adapted for engagement with clutch members 79 and 80 that are slidable on the countershaft 46 for rotation therewith, said clutch members being connected together by a slide 81 having forked ends 82 that engage annular grooves 83 in the respective clutch members, the arrangement being such that by moving the slide 81 either 105 the sprocket wheel 59 or the ratchet wheel 60 may be locked on the shaft for rotation therewith, or the clutch members 79 and 80 may be placed in a neutral position. For the purpose of actuating the slide 81 a bell 110 crank C is provided, said bell crank, as is clearly seen in Fig. 6, having arms 84 and 85 that are connected together by a cross bar 86. The arm 84 is connected by a link 87 with the slide 81; the arm 85 is connected by 115 a rod 88 with a hand lever 89; and the cross bar 86 is connected by a spring 90 with the frame of the machine, the tension of said spring being exerted; when the bell crank is slightly tilted about its fulcrum, to complete the tilting movement of said bell crank in either direction, thereby throwing one of the clutches 79 and 80 in engagement with the sprocket wheel 59 or the ratchet wheel 60, as the case may be. When the 120 clutch members are in neutral position, the spring 90 will be practically on a dead center, although it may, as shown in Fig. 6, be arranged slightly to one side of a dead center so that when the parts are otherwise 130

released, it will exert a tendency to tilt the bell crank in a direction to place the clutch member 80 in engagement with the ratchet wheel 60 which imparts movement in a rearward direction which is regarded as "feed" movement to the gate 57.

The lever 89 with which the forward end of the connecting rod 88 is connected has a stop member 91 that engages a single beveled notch 92 in a segment 93. Supported near the rearward and forward ends of the box or rack and extending upwardly through the slots in the bottom of said rack so as to lie in the path of the gate 57 are vertical levers 94 and 95, the former being connected with the connecting rod 88 by a link 96 and the latter being likewise connected with said connecting rod by a link 97.

Assuming now that the gate 57 is positioned near the forward end of the rack, as seen in Fig. 5, in engagement with the projecting upper end of the lever 95, the stop member 91 of the lever 89 should then be in engagement with the notch 92 of the segment 93 and the clutch members 79 and 80 should be in neutral position. Let it further be assumed that, the vehicle being in motion, the stop member 91 is released from the notch 92 and the upper end of the lever is moved in a rearward direction to pull upon the arm 85 of the bell crank C, the slide 81 will then be moved in the proper direction to cause the clutch member 80 to be placed in engagement with the ratchet wheel 60. The latter, being now locked on the countershaft 46, will cause the latter to be rotated in a proper direction to cause the gate 57 to travel in a rearward direction, the speed being capable of being regulated by means of the lever 76 and the mechanism hereinbefore described. When the gate reaches the rearward limit of its movement it encounters the upper end of the lever 94 which is thereby tilted, pulling on the connecting rod 84 and reversing the position of the bell crank C, the movement of the latter being completed by the action of the spring 90 as soon as the latter passes beyond a dead center. The clutch member 80 will thus be disengaged from the ratchet wheel 60 and the clutch member 79 will be placed in engagement with the sprocket wheel 59, locking the latter on the countershaft 46 and causing the latter to be rotated in a reverse direction. By the same pulling action on the connecting rod 88, the upper end of the lever 89 will be thrown in a forward direction, the stop member 91 jumping across the beveled notch 92 so as to engage the segment 93 in advance of said notch but without locking engagement with the segment. As the gate travels in a rearward direction it will presently encounter the upper end of the lever 95 whereby the connecting

rod 88 will be actuated in an opposite direction to its actuation by the lever 94, thereby pulling on the arm 85 of the bell crank C in a direction to move the clutch 79 out of engagement with the sprocket 70 wheel 59 and the clutch 80 in the direction of the ratchet wheel 60. The movement, however, will be interrupted by the movement of the stop member 91 with the notch 92 which occurs at the proper moment to arrest the movement of the slide 81 controlling the clutch members when the latter are in neutral position, thus interrupting further movement of the gate, the latter being at the forward limit of its movement 80 until it shall again be set in motion by a proper manipulation of the lever 89 on the part of the operator.

Supported in bearings on the rear cross bar 16 and on the top bar 22 are vertical 85 shafts 98 said shafts being provided at their lower ends with bevel gears 99 meshing with bevel gears 100 on the main shaft 30. The shafts 98 are provided at intervals with arms 101 carrying forks 102, said fork 90 arms constituting spreaders or scatterers which, when the shafts 98 are in motion, will be rotated in various horizontal planes, engaging the rearward portion of the load which is being moved rearward by the 95 action of the gate as previously described, the load being thereby scattered evenly over a large area, the quantity of material that is being scattered being capable of being very exactly regulated by the speed regulating means hereinbefore described.

From the foregoing description, taken in connection with the drawings hereto annexed, the operation and advantages of this invention will be readily understood. It 105 will be seen that I have produced a straw spreading machine capable of handling large quantities of straw mechanically and in a time and labor saving manner. It will furthermore be particularly noticed that when the machine is loaded and driven to the field, nothing remains to be done by the operator except to manipulate the lever 44 for the purpose of actuating the clutch whereby the main shaft is thrown in operation, and then to actuate the lever 89 whereby the feed mechanism is started in motion. The speed regulating means, having been once properly adjusted, usually requires little more attention, although it 110 is within the power of the operator to vary the speed of the feed movement at any time while the machine is in operation by means of the lever 76. The gate will continue its travel in a rearward direction until it 115 reaches the rearward limit of its movement, when, by the trip mechanism herein described, the direction of movement will be reversed and the gate will travel forwardly until the forward movement of its limit is 120 130

reached when, by reason of the automatic trip mechanism, its movement will be interrupted, thus enabling the vehicle to be driven to the loading place and reloaded without further attention to the mechanism.

Having thus described the invention, what is claimed as new is:

1. In combination, a driving shaft, a driven shaft, two members loosely mounted on the driven shaft, a clutch device slideable on the driven shaft and positioned between the two members loosely mounted on said driven shaft, means for actuating the clutch device to place said device in a neutral position or to engage the same with either of the members loosely mounted on the driven shaft, means for transmitting motion from the driving shaft to the driven shaft for rotating said driven shaft in one direction, means for transmitting motion from the driving shaft to the second member for rotating the driven shaft in the opposite direction, a member mounted for movement in opposite directions and operatively connected with the driven shaft, a bell crank, a hand lever, a rod connecting the hand lever and the bell crank, trip members intersecting the path of travel of the member operatively engaged with the members loosely mounted on the driven shaft, connections between said rod and the trip members, and a link connection between the bell crank and the clutch device.

2. In combination, a driving shaft, a driven shaft, two members loosely mounted on the driven shaft, a clutch device slideable on the driven shaft and positioned between the two members loosely mounted on said driven shaft, means for actuating the clutch device to place said device in a neutral position or to engage the same with either of the members loosely mounted on the driven shaft, means for transmitting motion from the driving shaft to the driven shaft for rotating said driven shaft in one direction, means for transmitting motion from the driving shaft to the second member for rotating the driven shaft in the opposite direction, a member mounted for move-

ment in opposite directions and operatively connected with the driven shaft, a bell crank, a hand lever, a rod connecting the hand lever and the bell crank, trip members intersecting the path of travel of the member operatively engaged with the members loosely mounted on the driven shaft, connections between said rod and the trip members, a link connection between the bell crank and the clutch device, and an actuating spring engaged with said bell crank and operating, when the bell crank has passed a dead center, to tilt said bell crank in the direction of the limit of its movement.

3. In combination, a driving shaft, a driven shaft, two members loosely mounted on the driven shaft, a clutch device slideable on the driven shaft and positioned between the two members loosely mounted on said driven shaft, means for actuating the clutch device to place said device in a neutral position or to engage the same with either of the members loosely mounted on the driven shaft, means for transmitting motion from the driving shaft to the driven shaft for rotating said driven shaft in one direction, means for transmitting motion from the driving shaft to the second member for rotating the driven shaft in the opposite direction, a member mounted for movement in opposite directions and operatively connected with the driven shaft, a bell crank, a hand lever, a rod connecting the hand lever and the bell crank, trip members intersecting the path of travel of the member operatively engaged with the members loosely mounted on the driven shaft, connections between said rod and the trip members, and a link connection between the bell crank and the clutch device, an actuating spring engaged with said bell crank and operating, when the bell crank has passed a dead center, to tilt said bell crank in the direction of the limit of its movement, and means for locking the hand lever against movement.

In testimony whereof I affix my signature.

STEPHEN J. FREEOUF.
